UNITED STATES PATENT OFFICE.

HARRIS B. HOLT, OF DORMONT, PENNSYLVANIA, ASSIGNOR TO ROSEDALE FOUNDRY & MACHINE COMPANY, OF PITTSBURGH, PENNSYLVANIA, A CORPORATION OF PENNSYLVANIA.

FURNACE CONSTRUCTION.

1,342,908.

Specification of Letters Patent. Patented June 8, 1920.

Application filed June 2, 1919. Serial No. 301,177.

To all whom it may concern:

Be it known that I, HARRIS B. HOLT, residing at Dormont, in the county of Allegheny and State of Pennsylvania, a citizen 5 of the United States, have invented or discovered certain new and useful Improvements in Furnace Constructions, of which improvements the following is a specification.

10 My invention relates to boiler furnaces of the general type wherein fuel is progressively fed from the front to the discharge side of a grate and wherein the ashes and clinkers are pushed from the discharge side 15 of the grate upon a support from which they are intermittently dumped into an ash pit below the grate.

In the operation of such furnaces considerable difficulty has been experienced largely 20 incident to the presence of clinkers upon or above the ash support. Occasionally the clinkers, as by arching above the ash support, prevent free and clean dumping of the ashes at each dumping operation, with the 25 result that a pile of ashes is found in the rear of the furnace. When the clinkers are finally dislodged, either by the weight of the accumulated ashes or by being poked loose, the falling body of ashes frequently causes 30 a portion of the fire bed to slip and fall into the ash pit. Not only does such disturbance of the fire bed interfere with the smooth running of the furnace, but the fire in the ash pit seriously damages the lower 35 portion of the furnace structure.

Furthermore, the hot burning clinkers resting upon the ash support, which is uncooled by air passing through it, rapidly burn out the support, and such burning is 40 hastened by the heated ashes and clinkers in the ash pit, particularly when a portion of the fire bed slips or is carried into the ash pit in the manner just explained.

The object of my invention is to provide, 45 for furnaces of the type described, means of a practical character for overcoming the above mentioned difficulties in furnace operation.

My invention is illustrated in the accompanying sheets of drawings in which Figure 50 1 is a vertical sectional view of a furnace, and Fig. 2 a plan view of the ash support and mechanism for moving it, the plane of view being indicated by the line II-II, Fig. 1.

The invention is applicable to various forms of furnaces of the general type explained above. The furnace, which, for the purposes of illustrating the invention, is shown in the drawings, is a forced draft furnace having an inclined grate, the front upper portion 1 of which is stationary, and the lower rear portion 2 adapted to reciprocate horizontally. Coal placed in a hopper 3 is intermittently discharged into the 60 furnace upon the forward grate 1 by means of plungers 4, each of which is connected by a link 5 to a crank arm 6, which arm is secured to a shaft 7 provided with a worm wheel 8. The worm wheel 8 is continuously 70 driven by means of a rotating shaft 9 adapted to drive a worm 10 secured to a shaft 11, which shaft in turn is provided with a worm shaft 12 meshing with the worm wheel 8. It will be understood that the shaft 9 75 extends along the front of the furnace and that a plurality of driving connections extend from it to a plurality of plungers 4 for feeding fuel to the furnace. The reciprocation of the grate bars 2 is effected in 80 coordination with that of the plungers 4, and to such end the grate bars are by means of rods 13 and links 14, 15 and 16 connected to the plungers. As indicated, the grates 1 and 2 are provided with suitable twyers 85 17 and 18 which communicate with the underside of the grate, which, in any desired manner, may be supplied with air under the required pressure for effecting a forced draft.

In the practice of my invention I provide at the rear of the grate a horizontally movable ash-receiving and supporting basin constructed to continuously contain water in free communication with the ashes and clinkers thereon. Means are provided whereby water may be continuously supplied in variable quantities to the basin, and also means are provided for moving the basin horizontally so as to permit the ashes supported thereby to fall into the ash pit 20 below the basin without dumping or otherwise removing the water from the basin.

As shown in Fig. 1, the basin is preferably constructed of an upper wall 21 and a lower wall 22, in the space between which walls water is supplied by means of a conduit 23 provided with a valve 24. To permit the basin to move horizontally a portion of the conduit 23 may be formed of flexible 110

tubing as shown in the drawings. The upper wall 21 of the basin is provided with perforations 25 through which water may flow to the upper face of such wall, and 5 such face is preferably provided with a plurality of ribs 26 spaced sufficiently close to each other to prevent relatively large burning clinkers from being immediately quenched by dropping into the water in the 10 top of the basin. The basin may be mounted upon a truck 27 supported by tracks 28, between which there is arranged a motive fluid cylinder 29 for reciprocating the basin. An arm 30 projects downwardly from the 15 basin and is connected to the outer end of a piston rod 31 attached to a piston 32. Pipes 33 and 34 are connected to the opposite ends of the cylinder 29, and through such pipes supply and exhaust motive fluid, 20 such as steam or compressed air, alternately flow to and from the cylinder 29, such flow being controlled by means of a valve 35.

The ash-supporting basin, rather than being placed immediately at the rear or discharge end of the grate, preferably forms 25 the bottom of an ash depository, one vertical wall of which may be formed by the furnace wall 36 and the other by an apron 37 extending downwardly from the rear end 30 of the grate. By providing a relatively large depository for ashes, the ashes need be dumped less frequently, which is of considerable advantage in the operation of forced draft furnaces in which it is necessary 35 to shut off the draft during each ash-dumping operation.

In operation, fuel is progressively fed from the front to the rear of the furnace by means of the reciprocation of the plungers 40 4 and grate bars 2. At the rear edge of the grate bars 2 the hot ashes and clinkers fall into the ash depository and upon the basin. The heat of such ashes and clinkers, as well as the heat of the furnace, vaporizes the 45 water supplied to the basin in free communication with the ashes, and the steam thus formed flows upwardly and disintegrates the clinkers so that the ashes dump freely at each dumping operation. When sufficient 50 ashes have accumulated to make it desirable to dump them into the ash pit, motive fluid is supplied through the pipe 34 to the cylinder 29 with the result that the basin moves horizontally immediately beneath the lower 55 edge of the apron 37, the apron serving as a pusher to remove the ashes from the top of the basin, the water, however, remaining in the basin. If desired, the basin may be thus moved through only a portion of its 60 maximum extent of travel, or in other words only a portion of the bottom of the ash depository may be removed. As soon as the ashes have been dumped to the extent desired, the pipe 34 may be opened to exhaust 65 and motive fluid supplied through the pipe

33 to the other side of the piston 32 to cause the basin to move back to its ash-receiving position. In case a portion of the fire bed slips into the ash pit during the dumping operation, sufficient water may be supplied 70 to the basin to cause the basin to overflow into the ash pit and extinguish the fire before the heat thereof damages the lower portion of the furnace structure. It will be observed that at all times the water supplied 75 to the basin cools the basin so that it does not burn out or become warped by the heat of the furnace.

According to the provisions of the patent statute, I have described the principle and 80 operation of my invention together with the construction which I now consider to represent the best embodiment thereof. However, I desire to have it understood that within the scope of the appended claims my 85 invention may be practised by other forms of construction than that specifically shown and described.

I claim as my invention:

1. In a boiler furnace, the combination of 90 a grate, means for progressively feeding fuel from the front to the discharge side thereof, a horizontally movable ash-receiving and supporting basin at the discharge side of the grate, means for supplying water 95 to said basin in free communication with the ashes supported thereby, an ash pit below said basin, an abutment adjacent to an upper edge of said basin, and means for moving said basin horizontally beneath said 100 abutment to cause the ashes supported by the basin to fall into said pit without removing the water from the basin.

2. In a boiler furnace, the combination of 105 a grate, means for progressively feeding fuel from the front to the discharge side thereof, an ash depository at the discharge side of the grate having one of its side walls formed of an apron extending downwardly from the rear of the grate, an ash-receiving 110 and supporting basin forming the bottom of said depository and horizontally movable immediately beneath the lower edge of said apron, means for supplying water to said basin in free communication with the ashes 115 supported thereby, an ash pit below said basin, and means for moving said basin beneath said apron to cause ashes supported by the basin to fall into said pit.

3. In a boiler furnace, the combination of 120 a grate, means for progressively feeding fuel from the front to the discharge side thereof, an ash-receiving and supporting basin at the discharge side of the grate constructed of a lower imperforate and an upper perforate wall, an ash pit below said basin, means for supplying water to the space between the walls of said basin, an abutment adjacent to an upper edge of said basin, and means for moving said basin 125 130

- beneath said abutment to cause the ashes supported by the basin to fall into said pit.
4. In a boiler furnace, the combination of a forced draft grate, means for progressively feeding fuel from the front to the discharge side thereof, an ash depository at the discharge side of the grate, the bottom of said depository being formed of a horizontally movable basin, means for supplying 10 water to said basin in free communication with the ashes supported thereby, an ash pit below said basin, an abutment adjacent to an upper edge of said basin, and means for moving said basin horizontally beneath 15 said abutment to cause the ashes supported by the basin to fall into said pit.
5. In a boiler furnace, the combination of a grate, means for progressively feeding fuel from the front to the discharge side thereof, an ash depository at the discharge 20 side of the grate having one of its side walls formed of an apron extending downwardly from the rear of the grate, an ash-receiving and supporting basin forming the bottom 25 of said depository, said basin being mounted on a truck and having its upper face im-
- mediately below the lower edge of said apron, means for supplying water to said basin in free communication with the ashes supported thereby, and means for moving 30 said truck horizontally beneath said apron to cause the ashes supported by the basin to fall into said pit.
6. In a boiler furnace, the combination of a grate, means for progressively feeding 35 fuel from the front to the discharge side thereof, a movable ash-receiving and supporting shallow basin at the discharge side of the grate, the upper face of said basin being provided with clinker supporting 40 ribs, means for supplying water to said basin in free communication with the ashes supported thereby, an ash pit below said basin, and means for moving said basin to permit the ashes supported thereby to fall 45 into said pit.

In testimony whereof I have hereunto set my hand.

HARRIS B. HOLT.
